METHOD AND APPARATUS FOR TRANSFER-
RING AND DELIVERING LATH TO PERFO-
RATING MACHINESLouis N. Sorensen, Port Clinton, Ohio, assignor to
The Celotex Corporation, Chicago, Ill., a corpo-
ration of Delaware

Application December 15, 1939, Serial No. 309,370

23 Claims. (Cl. 164—87)

My invention relates to a perforator transfer method and apparatus and in particular to the type of perforator transfer that may be used in the manufacture of perforated gypsum lath or the like.

In particular this invention relates to an apparatus for removing one or more gypsum lath from the main stream of manufacture, and feeding the lath so removed through the perforating mechanism described and illustrated in my application Serial No. 278,212 filed June 8, 1939.

The main object is to provide a means for removing one or more of a plurality of forward moving elements, such as gypsum lath or the like, from the main stream, performing any desired operation, such as perforating, on the elements so removed, and returning said elements to the main stream in synchronism with its forward movement.

A further object of the invention is to provide a method of operating on gypsum lath, the method or process consisting in removing one or more of a plurality of forward moving lath, from the main stream, performing any desired operation, such as perforating on the elements so removed, and returning said elements to the main stream in synchronism with its forward movement.

These and other objects and advantages may be noted from the following specification and its accompanying illustrations in which:

Figs. 1a, 1b and 1c show a continuous plan view of the perforator transfer apparatus, Fig. 1a showing the removing means, Fig. 1b showing the perforating means and Fig. 1c showing the returning means.

Figs. 2a, 2b and 2c show a continuous side elevation of Figs. 1a, 1b and 1c.

Fig. 3 is a cross sectional view partly in elevation on line 3—3 of Fig. 1a, of the apparatus for removing the lath from the main stream and delivering it to the conveyor which feeds it into the perforating mechanism.

Fig. 4 is a similar view to Fig. 3, but with the transfer mechanism in the raised position lifting the elements to be perforated, from the main stream.

Fig. 5 is a cross sectional view partly in section of the apparatus for actuating and timing the clutch operating mechanism and the mechanism which raises the lath above the supplementary transfer to permit lath not perforated to come onto the said transfer. This view taken approximately on lines 5—5 of Fig. 1c shows the clutch

engaged and the lath raising mechanism in lowered position.

Fig. 6 is a view similar to Fig. 5, taken approximately on lines 6—6 of Fig. 1c, but showing the clutch disengaged and the lath raising mechanism in raised position with the lath transversely on the supplementary transfer.

Again referring to the illustrations: the roller conveyor is indicated by the numeral 10, and receives thereon one or more strings of formed lath or elements 11, cut to suitable size; these lath are fed to the transfer 12 preparatory to being delivered over the tipple (not shown) into the drying kilns.

15 The forward end of the outside moving lath 11 strikes a trip or paddle 13 secured upon a rod 14 cross ways of the line of travel of said lath. The lath striking the paddle 13 causes said paddle to rotate, which also rotates a sprocket 15 secured on the end of the rod 14, causing a chain 16 mounted thereover, to be drawn upward over a sprocket 17.

20 The upward pull of the chain 16 raises a bar 18 to which the lower end of said chain is secured, the bar 18 which is hinged at 19, releases a clutch arm 20 from a catch 21 on said bar, thus disengaging the clutch arm 20.

25 A chain 22, to one end of which is attached a weight 23, is drawn down over a pulley 24 by said weight, causing the clutch arm 20, to which the opposite end of the chain 22 is attached to engage the clutch 25 on the shaft 26.

The shaft 26 is driven by a sprocket 27 through a chain 28 from the main board machine drive

30 35 The engagement of the clutch 25 drives a shaft 29 through the spur gears 30 and 31 and rotation of said shaft 29 drives a shaft 32 through sprockets 33 and 34 and a chain 35.

40 Also mounted on the shaft 32 is a second sprocket 36 which drives a series of shafts 37 through a sprocket 38 and chain 39. There are four shafts 37, each shaft end being mounted in bearings 40, said bearings being secured to cross members 41 above and 42 below; sprockets 38a are mounted on the outer ends of each shaft 37 and timing chains 43 and 43a are mounted thereover, one chain encircling the outer periphery of the four sprockets 38 on the one end and the other chain encircling the four sprockets 38a, on the opposite end of the shafts 37.

45 50 Actuating rod 44a is attached at one end to the chain 43a by a lug 45a, while rod 44 is attached to the chain 43 by a lug 45. The actuating rod 44a is pivotally secured at its opposite end to a

lever arm 46, said lever arm being mounted centrally of a shaft 47.

As the chains 43 and 43a travel, the rod 44a draws the lever arm 46 to the left causing elevating levers 48 and 48a, mounted at opposed ends of the shaft 47, to swing upward; this upward swing of the elevating levers 48 and 48a causes rods 49 and 49a, pivotally mounted on said levers at their lower ends, to move upwardly one end of the trolley carriage 50 and track 50a to which the opposite end of the rods 49 and 49a are attached.

Simultaneously a lever 51, mounted on the shaft 47 rotates; actuating an arm 52 pivotally mounted at one end on the lower end of the lever 51. A second lever 53 is centrally mounted on a shaft 54 and is attached at its upper end to the opposite end of the actuating arm 52. On the opposite ends of the shaft 54 are mounted a pair of levers 55, to the opposite ends of which are pivotally secured one end of actuating arms 56, the opposite ends of said arms 56 are pivotally secured on a rod 56a secured through the inner end of the trolley carriage 50. Thus as the front end of the trolley track 50a is raised by the action of the rod 44 rotating with the chain 43, the inner end of the carriage 50 is raised by the action of the numerous levers and arms hereinabove described.

The upward movement of the trolley carriage or track 50 raises a trolley buggy 57 which is slidably mounted between two trolley wheels 58 and 58a within the mounting 59.

To the top of a trolley 60, mounted over the outer end of the track 50a, is secured a pair of angles 61 and 62 which form a channel within which are secured trolley wheels 63 at each end. Cross bars 50b are pivotally secured to the buggy 57 at one end, their opposite ends secured to angles 60a secured to the trolley 60.

Secured to the trolley 60 are a series of racks 64 and 65 which move in unison with the movement of the trolley wheels 63 on the track 50a.

As the racks 64 and 65 are about to move upward and back to the position shown in Fig. 4, with the action of the levers which lift the trolley carriage 50 and track 50a, the racks 65 are elevated to a position slightly above the conveyer 10 and thus lift the outer or right hand length of lath 11 from the conveyer and at the same time lengths of lath 11 that have been deposited by the racks 64 and 65 on stationary racks 66 and 66a in previous cycles are lifted off of the said stationary racks 66 and 66a by the moving racks 64 and 65 as they move forward and drop down to and below the position shown in Fig. 3, thus depositing the selected length of lath 11 upon the rolls 67, as the lowest position is reached.

To more fully explain the operation of the removal of the lath 11 from the conveyer 10, the arrows on Fig. 4 indicate the direction of travel of the trolley 60, to which the moving racks 64 and 65 are secured; this outward movement of the trolley 60 takes place upon the completion of the upward movement of the trolley carriage 50 and trolley track 50a when the selected lath 11 is raised above the conveyer 10 by the upper moving rack 65 which also raises on its outer end, a lath 11 previously deposited upon the stationary rack 66.

Simultaneous with the raising of the lath 11 by the upper moving rack 65, the lower moving rack 64 lifts a lath 11 from the stationary rack 66a; the upward movement of the trolley track 50a and carriage 50 being thus completed, the out-

ward movement of the trolley 60, as indicated by the arrows, starts and the lath supported on the three levels of the trolley are thus carried outwardly.

When the outward movement is completed, the trolley track 50a and carriage 50 are gradually lowered to a position approximating that shown in Fig. 3, whereupon the lath 11 from the outer or right hand string is deposited upon the stationary rack 66 by the upper moving rack 65. The continued downward movement of said trolley track and carriage causes the upper moving rack 65 to deposit the lath 11, removed from the stationary rack 66, on the stationary rack 66a.

The completed downward movement of said trolley track and carriage causes the lower moving rack 64 to deposit the lath 11, lifted from stationary rack 66a, on the rollers 67, whereupon the cycle is again started by the inward movement of the trolley carriage and track as indicated by the arrows in Fig. 3.

The mechanism is so timed by the position of the lugs 45 and 45a on the chain 43 and 43a, that when the movable racks 64 and 65 have reached the top of their travel, the rod 44, movably secured to the trolley buggy 57, through the brackets 68, moves the said buggy outward. When the buggy 57 has reached the end of its outward travel, the chain 43a has reached a point

whereby the rod 44a actuates the lever arm 46 in an outward movement thereby lowering the carriage 50 and track 50a, this continuous movement causes the lifting of the lengths of lath 11 from the stationary racks 66 and 66a by the movable racks 64 and 65. This program of operation of the racks and buggy as just above described causes first the lifting of the lengths of lath 11 from the conveyer 10 and deposits same on the stationary racks 66, while at the same time a lath 11 will be lifted from the stationary racks 66 and deposited on the stationary racks 66a, both by the movement of the movable racks 65, and a lath 11 is lifted from the stationary racks 66a and deposited upon the auxiliary conveyer rolls 67 by the movable racks 64. Arrows on Figs. 3 and 4 indicate the direction of travel of the carriage and track.

As the chain 43a continues its travel, the rod 44a draws the lever arm 46 inwardly, this inward movement of the lever arm also draws the rod 44 inwardly; the catch 21 thereon engaging the clutch arm 28, disengaging the clutch 25 until the paddle 13 is again rotated by the lath 11.

Mounted on the shaft 26 is a sprocket 69 which drives a shaft 70 through a chain 71 and a large sprocket 72. A sprocket 73 mounted over the shaft 70 drives the rolls 67 through a chain 74 and sprockets 75 mounted on a roller shaft 79a.

The shaft 70 is mounted through a pair of bearings 76 within hangers 77.

A chain 78 drives rolls 79 through sprockets 80 and 81 on the roller shafts 67a and 79a.

The continuous chain 74a revolves sprockets 80a on the roller shafts 67a, while the continuous chain 78a revolves sprockets 81a on roller shafts 79a, which causes all the rollers 67 and 79 respectively to rotate simultaneously.

As the racks 64 deposit the lath 11 on the rolls 67, a lever arm 82 attached to the channel, formed by the angles 61 and 62, move downward causing a chain 83 to pull upward through the lever 84 and a pair of pulleys 85 and 86 raising an arm 87 to which the end of the chain 83 is attached below a weight 88. A pulley wire 89 is secured to the arm 87 at one end, the opposite

end being secured to a clutch arm 90 around a pulley 91.

A tension spring 92 is secured to the floor 93 at one end, the opposite end is attached to the clutch arm 90, thus when the weight 88 raises with the chain 83, releasing the tension on the clutch arm 90, the tension spring 92 draws the said clutch arm 90 to the left causing a clutch 94 to engage.

The engagement of the clutch 94 causes a chain 95 to drive the perforator mechanism 150 through the sprocket 96. The action of said perforator mechanism 150 is fully explained in my application, Serial No. 278,212, filed June 8, 1939.

To operate the perforating mechanism, the chain 97 traveling over the sprocket 98 carries an angle 99 which at the completion of the travel of said chain, engages the arm 87, drawing it forward and causing the clutch 94 to be disengaged thereby stopping the perforation until another lath 11a is deposited upon the rolls 67 by the racks 64.

After the lath 11a are carried through the perforating mechanism 150 by the chain 100 and the lugs 101 thereon, the said lath are picked up by the rolls 102 and 102a and carried along toward the transfer 12.

A motor 104, mounted on the cat walk 105, drives a shaft 106 through a belt 107 and pulley 108; a sprocket 106a on the shaft 106 drives a shaft 109 through a chain 110 and sprocket 111 which is controlled by a clutch 112.

The rolls 102, 102a and 103 are driven by the motor 104 through the clutch 112 which is timed by a chain 113, the action being as follows: as the main stream of lath approach the transfer A from the perforator, a beam from a photo electric cell (not shown) is broken which starts a system of timing switches so that when the main stream of lath reaches the end of the transfer, a series of plates 114 beneath the transfer belts 115 are raised, lifting the lath 11 above the rolls 116, simultaneously a motor (not shown) starts driving shafts 117 having pulleys 118 thereon.

Lath for perforating are removed only from each alternate series of three lath after they have been cut to length so that a full three lath are delivered to the transfer A followed by two lath.

As the shaft 117 rotates a sprocket 119, it drives the chain 113 which is held in tension by an idler roller 120. As the said chain 113 moves, the lug 121 secured thereto, forces a lever arm 122 pivoted at 123, forward, causing a catch 124 on an operating rod 126, to engage a clutch lever 125, moving it forward to engage the clutch 112 and start the rolls 102, 102a and 103.

The roll 102a has collars 127 thereon to iron out any unevenness in the lath 11a caused by the perforating operation.

The lath 11 move forward on supplemental conveyer rolls 103 driven by the chain 128 until the end of the lath strikes the paddle 129 mounted on a shaft 130; the pivoting of the paddle, rotates a sprocket 131 pulling upon a chain 132 over the idler roll 132a and disengaging the catch 124 from the clutch lever 125.

A tension spring 133 draws the clutch lever 125 to the left where the catch 124 is released from the clutch lever 125, disengaging the clutch 112 and stopping the rotation of the rolls 102, 102a and 103.

Following or contemporaneous with the arrival of the perforated lath 11a on the ancillary trans-

fer B, a full complement of three lath arrive on the main transfer A, the plates 114 lifting, the belts 115 rise, and the three lath 11 are moved sidewise on the belts 115 while the single perforated lath 11a is moved upon the lifting rack 134.

Mounted on the shaft 117 is a sprocket 135 driving a timing chain 136 over an idler roller 137, thus when the perforated lath 11a reaches a position over the lifting rack 134, a lug 138 on the chain 136 strikes the end of a lever 139 which is pivoted at 140.

A drawing to the right of a link 141 causes a rotation of a pair of cams 142 on a shaft 143 through a cam lever 144; rotation of the cams 142 on the shaft 143, raises the lifting rack supports 145 and 145a mounted on a cross bar 146 thus elevating the lifting rack 134 and lifting the perforated lath 11a from the rolls 103.

20 The lifting rack support 145a is attached to the bottom of the plates 114 for the belts 115 and as these plates lower, the cams 142 act partially as pivoting points to raise the lifting rack 134.

25 After the lath 11, on the transfer A, is moved sidewise by the belts 115, a string of two lath 11 are delivered by the side of the perforated lath 11a to make a full complement of six lath on the transfer, the six lath are again moved slightly sidewise to place them in position to be delivered 30 to the tipple (not shown). This second sidewise movement releases the lever 139 from the lug 138 on the chain 136 and the lifting rack 134 drops down and out of the way of the forward moving rolls 116 and the lath are then delivered 35 to the tipple by rotation on the rolls 116.

This machine is arranged so as to lower the lath to the elevation of the perforator. However, it is to be understood that the same principle of operation could be used if the perforating mechanism were on the same level as the board machine or above it.

40 In the foregoing description, I have embodied the preferred form of my invention, but I do not wish to be understood as limiting myself thereto, as I am aware that modifications may be made 45 therein without departing from the principle or sacrificing any of the advantages of this invention, therefore, I reserve to myself the right to make such changes as fairly fall within the scope thereof.

50 I claim:

1. The combination of a main conveyer adapted to convey a line of articles along the same, an auxiliary conveyer beside the main conveyer, and 55 means to select some of said articles from the main conveyer at predetermined intervals and transfer said selected articles from the main conveyer to the auxiliary conveyer according to the predetermined selection, for an additional operation on said selected articles.

60 2. The combination stated in claim 1, and means to return said selected articles from the auxiliary to the main conveyer, after such operation.

65 3. In a machine for conveying lath or the like and perforating selected lath so conveyed, the combination of a main conveyer adapted to convey a line of formed lath, an auxiliary conveyer beside the main conveyer, means to select some 70 of said articles from the main conveyer at predetermined intervals and transfer said selected lath from the main conveyer to the auxiliary conveyer, and means associated with the auxiliary conveyer to perforate the lath so transferred.

75 4. The combination stated in claim 3, and

means to return the perforated lath from the auxiliary conveyer to the main conveyer.

5. The combination stated in claim 3, and means to return the perforated lath from the auxiliary conveyer to the main conveyer, said means including a supplemental transfer conveyer to which the perforated lath are delivered from the auxiliary conveyer.

6. The combination of a main conveyer adapted to convey a row of separate articles along the same, an auxiliary conveyer extending beside the main conveyer, and means to select and lift some of the articles from the main conveyer at predetermined intervals and transfer the same laterally onto the auxiliary conveyer for an additional operation on said selected articles.

7. The combination stated in claim 6, and means to return said selected articles after such additional operation from the auxiliary conveyer to the main conveyer.

8. The combination stated in claim 6, and means associated with said auxiliary conveyer to perforate said selected articles.

9. The combination of a main conveyer having spaced rollers on which articles travel, an auxiliary conveyer beside the main conveyer, and means to transfer selected articles from the main conveyer to the auxiliary conveyer, said transfer means including racks movable upwardly between the rollers, to lift articles therefrom, and laterally to deposit said articles on the auxiliary conveyer.

10. The combination stated in claim 9, and means to time the movement of the transfer racks according to a predetermined plan, whereby selected articles will be transferred from the main line of articles on the main conveyer.

11. The combination stated in claim 9, and means to time the movement of the transfer racks according to a predetermined plan, said means including a trip mechanism actuated by articles on the main conveyer.

12. The combination of a main conveyer adapted to convey a series of articles in multiple rows side by side, an auxiliary conveyer extending along one side of the main conveyer, and means to transfer selected articles according to a predetermined plan from one of said rows to the auxiliary conveyer, for an additional operation thereon.

13. The combination stated in claim 12, the main conveyer having spaced rollers, and the transfer means including racks movable upwardly between the rollers to lift the selected articles therefrom and laterally to deposit said articles on the auxiliary conveyer.

14. The combination stated in claim 12, the main conveyer having spaced rollers, and the transfer means including racks movable upwardly between the rollers to lift the selected articles therefrom and laterally to deposit said articles on the auxiliary conveyer, and means automatically operated by the movement of the main conveyer to time the movement of the transfer racks according to a predetermined plan.

15. The combination of a main conveyer adapted to convey a line of articles along the

same, an auxiliary conveyer extending beside the main conveyer and parallel thereto, and means to intermittently transfer selected articles from the main conveyer to the auxiliary conveyer, said

5 transfer means including racks working across between the main and auxiliary conveyers in a quadrilateral line comprising an initial lifting movement, a lateral horizontal movement, a descending movement, and a return horizontal

10 movement to original position.

16. The combination stated in claim 15, and means automatically actuated by the movement of the main conveyer to time the operation of the transfer means according to a predetermined plan.

15 17. In a machine for conveying and perforating formed lath or the like, the combination of a main conveyer along which a row of lath is conveyed, an auxiliary conveyer beside and parallel to the main conveyer, means to select some of the said articles from the main conveyer at predetermined intervals and transfer said selected lath from the main conveyer to the auxiliary conveyer, a perforating mechanism associated with the auxiliary conveyer and acting to perforate the selected lath, and a return transfer means between the auxiliary and main conveyers acting to return the perforated lath from the former to the latter.

20 18. The combination stated in claim 17, and an ironing roller between the perforating machine and the return transfer mechanism to smooth any unevenness in the lath caused by the perforating operation.

25 19. The combination of means to convey lath or the like in rows, a perforating machine, means to intermittently transfer lath from a row to the perforating machine for perforation thereof, and means to return the perforated lath to the original row.

30 20. The combination stated in claim 1, and means to assemble said selected articles, after such additional operation, with the articles delivered from the main conveyer.

35 21. The combination of means to convey a plurality of rows of articles, means to remove a selected article from one of the rows, means to convey this article to a station for operation thereon, and means to return said article to its place in the original row.

40 22. The method of operating upon a moving stream of similar articles, comprising conveying a continuous primary stream of such similar articles, intermittently removing selected articles from said stream according to a predetermined plan, conveying said removed articles along a secondary path for operation thereon, and then returning said selected articles to the original stream.

45 23. The method according to claim 22, the movement in the secondary path being timed to return the selected articles to the primary stream in the same relative position therein that such articles occupied at the time of removal from the primary stream.

50 65 LOUIS N. SORENSEN.
